SIGN

George P. Marsden, 4604 Drummond Ave.,
Chevy Chase, Md. 20015

Filed Sept. 13, 1967, Ser. No. 8,584

Term of patent 14 years

(Cl. D96—12)

FIG. 1 is a side elevational view of a sign showing my new design;

FIG. 2 is a front elevational view, the rear view being the same;

FIG. 3 is a perspective view;

FIG. 4 is an enlarged fragmentary cross-sectional view taken on lines 4—4 of FIG. 2;

FIG. 5 is an enlarged fragmentary cross-sectional view taken on lines 5—5 of FIG. 2; and

FIG. 6 is an enlarged fragmentary cross-sectional view taken on lines 6—6 of FIG. 2.

I claim:

The ornamental design for a sign, as shown and described.
